DRAWBAR HINGE FOR TRUCK TRAILERS
AND THE LIKE

Henry C. Harbers, Pasadena, and Buck C. Hamlet, La Puente, Calif., assignors to Western Unit Corporation, City of Industry, Calif., a corporation of California
Filed Oct. 19, 1959, Ser. No. 847,366
9 Claims. (Cl. 280—485)

This invention relates to a drawbar hinge construction for truck trailers and the like.

An object of the present invention is to provide a strong, simple and safe drawbar hinge which performs the functions of prior-art hinges, and other functions, yet which may be manufactured for approximately 50% of the cost.

Another object of the invention is to provide a drawbar hinge which requires no machining operations, and which is characterized by high strength and low weight.

Another object of the invention is to provide a drawbar hinge which is extremely simple to assemble despite variations in the relative positions of the elements, and which does not require that a pin or the like be inserted from one end to thus necessitate provision of clearance adjacent such end.

Another object is to provide a drawbar hinge which is easy to disassemble even after long periods of use under high stresses.

Another object is to provide a drawbar hinge incorporating means to hold the drawbar or tongue at a desired elevated condition for coupling with a truck, yet which does not impede operations of the hinge should such means become inoperative.

An additional object is to provide a drawbar hinge incorporating elastomeric bushing elements which may be formed economically as extrusions, and which permit assembly of various parts of the hinge in different rotated positions as required by the particular truck-trailer assembly.

These and other objects and advantages of the invention will be more fully set forth in the following specification and claims, considered in connection with the attached drawings to which they relate.

In the drawings:

FIGURE 1 is a top plan view illustrating a drawbar hinge constructed in accordance with the present invention, a portion of one pressure plate being broken away;

FIGURE 2 is a vertical section taken on line 2—2 of FIGURE 1;

FIGURE 3 is a vertical sectional view corresponding to FIGURE 2 but illustrating the positions of the parts after the tongue has been released to permit downward pivoting thereof until the elastomeric protuberances become operative to limit such pivoting;

FIGURE 4 is a vertical sectional view taken longitudinally of the hinge, on line 4—4 of FIGURE 3; and

FIGURE 5 is a perspective view illustrating one of the elastomeric cushion or bushing elements.

Referring to the drawings, it is pointed out that the hinge has only six parts, in addition to four standard bolts and the associated nuts. Such parts comprise four castings which require no machining, and two sections of an elastomeric extrusion. The castings include a hinge bracket 10, a hinge pin 11, and two pressure plates 12. The sections of elastomeric extrusion, which perform the functions of cushions or bushings adapted to limit relative rotation between hinge pin 11 and bracket 10, are numbered 13.

Proceeding first to a description of the hinge bracket 10, this comprises an elongated body 15 having flanges 16 formed integrally at both ends thereof. The flanges

2

16 are parallel to each other and spaced a substantial distance apart, and each is formed with a recess adapted to receive a cushion or bushing member 13. Stated otherwise, each of the flanges 16 is so shaped that it forms four walls of a six-walled chamber in which each cushion member 13 is confined as will be described subsequently. The remaining two walls of each chamber are formed by the hinge pin 11 and a pressure plate 12.

Stated more definitely, the four recess or chamber walls 10 formed by each of the flanges 16 comprise a bottom wall 17 (FIGURES 2—4), an end wall 18 (FIGURES 1 and 4), and two side walls 19 one of which is illustrated in the broken-away portion of FIGURE 1.

The hinge pin 11 is an elongated tube having end portions 21 disposed in the above-indicated recesses or chambers but spaced substantial distances inwardly from the walls thereof. The hinge pin has a central portion provided with a plurality of large-diameter annular flanges or ribs 22 two of which are disposed sufficiently close 20 to the flanges 16 to form the opposite end walls of the above-indicated recesses or chambers. Stated otherwise, two of the ribs, numbered 22a and 22b, are disposed opposite the first-mentioned end walls 18 and form the remaining end walls.

25 The flanges or ribs 22 of the hinge pin 11 are integral with a connector portion 23 to which is welded or otherwise rigidly secured one of the drawbar or tongue members 24 of the apparatus. It is to be understood that the hinge bracket 10 is rigidly secured by means, not shown, 30 to one end portion of the front wheel bolster of the trailer. Furthermore, a second and corresponding hinge bracket (of the second and corresponding drawbar hinge construction) is rigidly secured to the other end portion of the front wheel bolster. Each of the drawbar hinges 35 is associated with one of the drawbar or tongue members 24, such members converging forwardly (in a tongue) to an apex point at which is located the means for securing the tongue to the truck body. The hinge brackets 10 of the two hinge assemblies are so oriented 40 that the hinge pins 11 are coaxial and horizontal, and are parallel to the common axis of the front wheels of the trailer. The tongue may therefore pivot upwardly and downwardly about a horizontal axis through both hinge assemblies.

45 The pressure plates 12 comprise generally rectangular members adapted to seat over the flanges 16 to form the top walls of the chambers containing elastomeric cushions or bushings 13. Four bolts 26 are extended downwardly through the pressure plates 12 and through suitable vertical bores in the flanges 16, being associated 50 with nuts 27 located beneath the flanges. Tightening of the threaded fasteners 26—27 forces the pressure plates downwardly and produces important extrusion effects relative to elastomeric elements 13.

55 Each elastomeric cushion or bushing 13 is formed of a durable and strong elastomer such as neoprene, and is generally tubular in shape except that it is made square or flat on one side (FIGURE 5). Each such member 13 has a central cylindrical opening 28 the diameter of 60 which corresponds generally to that of a tubular end portion 21 of hinge pin 11. Each opening 28 is sufficiently large that the hinge pin may rotate therein.

The squared or flat side of each member 13 is indicated at 29, and is adapted to be disposed beneath a 65 pressure plate 12.

It is an important feature of the invention that means are provided on each pressure plate 12, recess bottom wall 17, and hinge pin end 21 to effect deformation or extrusion of elastomeric material 13 in such manner as 70 to form deformed portions 31 adapted to limit rotation of the hinge pin 11 relative to the bracket 10. Such means comprise frusto-conical protuberances 32 formed inte-

grally and diametrically opposite each other on each plate 12 and on the bottom wall portion 17 of each flange 16. Openings or recesses 33 are formed opposite each other in each end portion 21 of the hinge pin, and have shapes and sizes corresponding generally to the protuberances 32. It follows that upon downward shifting of each pressure plate 12 due to tightening of the fastener assemblies 26—27, the portions 31 of elastomeric material will be deformed or extruded into the openings 33 as shown in FIGURES 2—4.

It is emphasized that there is a substantial distance between the inner surfaces of protuberances 32 and the exterior cylindrical surface of each pin end portion 21, so that a relatively large mass of elastomeric material is disposed therebetween. This is important not only to the strength of the assembly, but to permit the rubber to be deformed circumferentially as well as radially-inwardly as will be described subsequently with relation to FIGURE 2.

Operation

As previously stated, the elements 10—12 are castings and require no machining whatsoever. Let it be assumed that the hinge brackets 10 of two of the drawbar hinge assemblies have been suitably mounted on opposite end portions of the front wheel bolster of the trailer. Let it also be assumed that the portions of members 24 at both ends of the V-shaped tongue have been welded to the connector portions 23 of pins 11 of the hinge assemblies.

To mount the hinge pins 11 in the hinge brackets 10, it is merely necessary to position elastomeric cushions 13 on the pin end portions 21, and then dispose such members in the above-defined recesses or chambers in flanges 16. This assembly operation is so conducted that the squared portions 29 of the cushions 13 are disposed upwardly. It is pointed out, however, that the tongue may at this time be rotated to any elevation without causing rotation of the cushions 13 since the pin ends 21 may rotate in openings 28.

Let it be assumed that it is desired that the tongue be approximately in a horizontal plane when the trailer is coupled with the truck, although it is to be understood that the parts may be so assembled that the tongue will be in substantially any plane. The cover plates 12, bolts 26 and nuts 27 are then loosely assembled, and the tongue is inclined upwardly from the horizontal as indicated in FIGURE 2. The bolts 26 and nuts 27 are then tightened to force all of the pressure plates 12 downwardly to the illustrated positions. Since each of the cushions or bushings 13 is confined as stated previously, downward movement of the cover plates causes extrusion of portions of the rubber into the openings 33 in pin end portions 21. As illustrated in FIGURE 2, such extrusion results in creation of substantial deformed portions 31 despite the fact that the protuberances 32 are not directly opposite the openings 33.

The weight of the tongue may then be released, which causes downward gravitational pivoting of the tongue to the position shown in FIGURE 3. The shear forces thus generated in the cushions 13 adjacent deformed portions 31 cause the tongue to remain substantially horizontal, as shown in FIGURE 3, though it is not supported in any manner except by the deformed portions 31 and related parts. It is thus possible for a single operator to couple a truck with the tongue.

From the above it will be understood that the hinge pins 11 may be assembled with the hinge brackets 10 in a highly simple manner, without requirement that the parts be precisely located, and without requirement that a pin be inserted through one end of each bracket. It is, therefore, unnecessary to provide clearance room adjacent the ends of the brackets. If it is desired to disassemble a hinge assembly, it is merely necessary to remove the fasteners 26—27 and cover plates 22, and

4
pry the hinge pin 11 upwardly so that the cushions 13 spring out of the recesses in flanges 16.

Should it occur that the deformed portions 31 shear off, the function of the hinge assembly in coupling the trailer to the truck is not impeded in any way, and the safety of the hinges is not diminished. Furthermore, such shearing of the deformed portions 31 does not tend to prevent pivotal movement of the tongue upwardly when desired. This is to be contrasted with certain constructions which, when they malfunction, not only do not support the tongue above the ground but tend to prevent upward pivoting of the tongue to a substantially horizontal plane.

It is emphasized that, in service, the cushions 13 perform important functions of eliminating shocks, reducing wear and noise, etc. Since they are extrusions and not molded parts, they are extremely economical and may be replaced with very little effort, as stated above.

With reference to the following claims, the term "recess" shall be construed to include "opening," and vice versa, with relation to elements 33 or equivalents thereof.

Various embodiments of the present invention, in addition to what has been illustrated and described in detail, may be employed without departing from the scope 25 of the accompanying claims.

We claim:

1. A drawbar hinge for truck trailers and the like, comprising a cast metal hinge bracket adapted to be secured to a trailer, said bracket having spaced flanges disposed opposite each other, each of said flanges being shaped to define the bottom wall, the opposed end walls and two side walls of a chamber, the inner end wall and the top wall of said chamber being open, a T-shaped cast metal hinge member having end portions extending 30 into said chambers through said open inner end walls thereof, said end portions of said hinge member having radial recesses formed therein, the center portion of said hinge member having enlarged wall means adapted to close substantially said inner end walls of said chamber, 35 said center portion of said hinge member being adapted to be connected to a portion of a drawbar, elastomeric extrusions mounted around said end portions of said hinge member in said chambers and abutting said walls of said chambers, pressure plates disposed over said top walls of said chambers and having inwardly-extending protuberances disposed outwardly from said recesses in said hinge member end portions, and fastener means to secure said pressure plates to said hinge bracket and to force said pressure plates inwardly and thereby effect extrusion of portions of said elastomeric extrusions into said recesses in the ends of said hinge member.

2. The invention as claimed in claim 1, in which the outer portions of the ends of said hinge member are spaced substantial distances inwardly from said protuberances, thereby permitting extrusion of elastomeric material into said recesses despite substantial offsetting between said end portions and said protuberances.

3. A drawbar supporting hinge adapted to be attached between a towed vehicle and the drawbar thereof, said hinge comprising a pair of main castings the first of which is adapted to be rigidly secured to an end of a towed vehicle and the second of which is adapted to be rigidly secured to the adjacent end of a drawbar used to tow the vehicle, the first casting being generally rectangular in shape and open along one of its longer lateral faces and centrally of an adjoining longer lateral face with the two openings merging with one another at their adjacent edges, the second casting being generally T-shaped and having separate unitary elastomeric collars insertable axially over the opposite ends of the head thereof, the collars and head of said T-shaped second casting being insertable with a press fit laterally through the open face of said first casting with the stem of said T-shaped member protruding outwardly through the central opening in the adjoining face of said first casting, and pressure plate means

for locking said assembled components firmly pressed together by pressure applied radially to said collars across the ends of said open face of said first casting.

4. A drawbar hinge assembly comprising a pair of main casting adapted to be assembled into a hinge assembly without need for machining operations, said castings including a main casting having a generally rectangular cavity opening through one longer face thereof, an adjoining longer face of said casting having an opening merging with one of the long side edges of the opening into said rectangular cavity, a T-shaped second casting having separate unitary elastomeric collars snugly seated over the opposite ends of its head portion and shaped to seat snugly within the opposite ends of said rectangular cavity with the stem of said T-shaped member protruding through the opening centrally of said main casting and lying normal to the longitudinal axis of main casting, and clamping means for holding said elastomeric members pressed tightly into the opposite ends of said cavity and gripping the opposite ends of said T-head in a manner resisting relative rotation of said two castings about the longitudinal axis of the head of said T-shaped member.

5. A drawbar hinge as defined in claim 4 characterized in that at least one of said castings and one of the cooperating non-elastomeric components of said hinge assembly have generally complementally shaped cooperating protrusions and cavities opposite axial surfaces of said elastomeric members, said clamping means being effective upon said elastomeric members to press said protrusions into said members to compress the same causing the latter to expand radially into said complementally-shaped cavities thereby interlocking the components of said hinge assembly against relative movement.

6. A joint assembly wherein the two principal components are separated from one another by compressed elastomeric material cooperating to limit relative movement between said principal components, one of said principal components being a hollow, generally rectangularly shaped member open substantially throughout one longer face and including a notch leading therefrom centrally across an adjoining longer face, the other principal component being generally T-shaped and including a pair of elastomeric collars seated on the opposite ends of its head portion having an exterior shape complementary to that of the interior opposite end portions of said rectangular member, the head of said T-shaped member with its elastomeric collars being insertable as a unit

laterally through the open face of said rectangular member with its stem portion extending through the notch across said adjoining face with its axis normal to the longitudinal axis of said one principal component, and 5 means for clamping said components so assembled and for placing said collars under radial compression.

7. A joint assembly as defined in claim 6 characterized in that said pair of principal components comprise metal castings assembled together without need for machining 10 or metal finishing operations and separated from one another by said elastomeric collars.

8. A joint assembly as defined in claim 6 characterized in that said collars are generally circular and provided with a wide flat-surfaced boss projecting from the 15 circumference thereof adapted to lie parallel and close to the open face of said first principal component in the assembled position of the components, and said clamping means bearing against the wide flat-surfaces of said collars to compress the material thereof and to place the same 20 under high pressure contact with the opposite ends of the head of said T-shaped member and with interior surfaces of said rectangular member.

9. A joint assembly as defined in claim 6 characterized in that surfaces of said two principal components in contact with axially disposed surfaces of said collars are formed one with radially projecting bosses and the other with similarly shaped cavities whereby the clamping of said collars in a manner placing them under radial compression acts to depress said bosses into the collars and 25 to displace an equivalent volume of said collars thereby aiding materially in expanding other portions of said collars into said cavities to provide effective positive interlocks between said collars and said two principal components.
